REVERSIBLE HEATING AND COOLING
SYSTEM

Frank A. Krueger, Shawano, Wis.

Application May 5, 1948, Serial No. 25,283

10 Claims. (Cl. 62—129)

1

This invention relates to a reversible heat pump. More particularly, it relates to a heat pump, primarily for installation in private homes, which employs a compressor and two sets of coils which may be used interchangeably as evaporators or condensers. Applicant's system employs water drawn from the earth for providing heat or removing heat.

The first object of this invention is to provide an open duct refrigerating system, by which applicant means one which has neither check valves, nor expansion valves, nor float valves between the low side of the compressor at one end of the refrigerating system and the high side of the compressor at the other end of the refrigerating system. This objective is important in a refrigerating system. In the ordinary system, such as in a household refrigerator, any number of check valves, float valves, or expansion valves may be inserted in the system because the flow of refrigerant is always in one direction. In the reversible heat pump, the flow is in either direction. If the line contains several check valves and float valves, which will cause the system to function when the refrigerant is flowing in one direction, these valves must be rendered inoperative and other valves brought into operation if the system is to function in the reverse direction.

Another feature of applicant's invention is what he refers to as his "balanced system" by which he means the provision of two sets of coils and accumulators which have approximately the same volumetric capacity in a refrigerant line which has no valves in it, with the result that the system can go from a heating system to a refrigerating system by simply reversing the direction of flow of refrigerant. The operation of the device will be explained in the description.

The second object of this invention is to provide a muffler which will kill the pounding noise of the pump when forwarding refrigerant to the coils. In an ordinary refrigerator the output on the high side of a piston type pump leads to the condenser coils, which in turn feed an accumulator. Each time the pump forces a quantity of gas into the tubing of the condenser there is a throb or noise. The noise is not great in the case of small compressors. In heat pumps, however, where one is using four cylinder pumps driven by four or five horsepower motors, this throb is very noisy. One of the features of applicant's invention is positioning an accumulator between the coils and the high side of the pump. This accumulator acts something like an automobile muffler. The compressed gas is forced into the

2

accumulator and is then carried out a plurality of passageways into the condenser.

The third object of this invention is to provide a system which circulates water from the ground to the point of use and back into the ground. Many of the heat pumps that rely upon water for withdrawing heat from the earth position a water line and return water line, that is a closed circuit, down into the earth for several hundred feet. The ability of these systems to function depends on the rate of heat transfer from the earth through the pipe into the water. Applicant's system does not employ such a closed pipe circuit. On the contrary, applicant's system draws water from the ground, twenty-five feet or so below the surface, uses it, and then puts it back into the ground twenty-five feet below the surface at some distance from where it was taken out.

20 The foregoing objects have all been attained, for the invention here disclosed was built by applicant and placed in operation at applicant's home at Shawano, Wisconsin, in the fall of 1947. The device has heated a story and half house, 25 seven rooms, with a basement approximately thirty-four feet square, to an average temperature of 72 degrees when outside temperatures were as low as 27 degrees below zero. The cost of electricity has averaged approximately 41 cents a day.

30 In the description that follows, applicant's system is described in two ways, first schematically, in connection with Figs. 1 and 2; and secondly, factually, in connection with Figs. 3, 4 and 5, which are plan, side and end elevations of the system installed in applicant's home at Shawano.

35 Continuing to refer to the drawings, in Fig. 1, the numeral 10 identifies a compressor and the numerals 12 and 14 identify heat exchange units. 40 Each heat exchange unit consists of a battery of coils 16 and 18 connected to accumulators 20 and 22. The coils 16 and 18 are connected to each other by a capillary tube 24. The accumulators are connected to a reversing assembly 26 which in turn is connected to the compressor 10.

45 It will be noticed that there are no valves in the system, other than the reversing valves, or the valves in the compressor. There are no check valves or expansion valves. For this 50 system to work, the important thing is this: The cubic content of the heat exchanger 12 which includes the coil 16 and the accumulator 20 should be approximately equal to the cubic content of the heat exchanger 14 which includes the coils 18 and the accumulator 22. It is not neces-

sary that the cubic content of the accumulator 20 be equal to that of the accumulator 22 or that the content of the coil 16 be equal to the content of the coils 18. If the heat exchanger 12 is positioned in a flow of air, the rate of heat transfer is slower than the rate for the coils 18 if they are positioned in water, and applicant, consequently, may utilize coils having less cubic content in the heat exchanger 14 than the cubic content of the coil 16.

Assuming that the reversing valve is set so that the line 33 is connected to the low side 27 of the compressor, and the line 31 is connected to the high side 29 of the compressor, if equal quantities of liquid refrigerant are positioned in the two heat exchangers 12 and 14, the liquid level will be along the line 32 in accumulator 22 and along the line 34 in coil 16. The refrigerant will be boiling in the accumulator 22 as it and its coils 18 pick up heat from water in which they are immersed and the liquid and gas in the coil 16 and accumulator 20 will be hot and transfer heat to air passing over the coils and accumulator. The liquid in coil 16 will flow through the capillary to the coil 18.

If the reversing valve is placed in its alternative position, whereby conduit 31 is connected to the low side 27 of the pump and conduit 33 is connected to the high side 29, the liquid level will assume the positions indicated by the lines 36 and 38 in Fig. 2. In Fig. 2, the heat exchanger 12 is now withdrawing heat from the house air which flows over it, which heat is being transferred to the heat exchanger 14 which is losing the heat into the water in which the exchanger is positioned.

This system has been embodied in the installation shown in Figs. 3, 4 and 5. Referring to Fig. 4, the numeral 40 identifies a pipe carrying a point 42 which has been driven into the ground for whatever distance is necessary to reach water. It is not necessary to reach the depth of pure water. Any water will suffice. This ordinarily is an inexpensive operation. The pipe 40 is in sections and may be driven into the earth with a sledge hammer. The pipe is connected to a suction pump 44 which is driven by a motor 46. The output of this pump is taken by a flexible hose 48 into a stock tank 50. The stock tank has an outlet 52 near its bottom which is carried upwardly, externally of the tank to the point 54 which is the water level at which applicant desires the tank to operate, whereupon the water is carried along the drain 56 to a second pipe 58 with point 60 which has been driven into the ground at a point perhaps 100 feet of more from the pipe 40.

As the water system is here shown, the tank 50 is open topped and the pump 44 performs solely the function of raising the water out of the ground. The water returns to the ground by gravity. Actually, applicant has been delivering the water at approximately the point 62 into a drain which carries it away from his property as surface water. The arrangement shown in Fig. 4 is of great importance because the water table in many areas has been dropping in recent decades due to the increase in the amount of pumping of water to the surface. Communities are taking steps to protect their water table. The water table that is important to communities is the water that is several hundred feet below the surface where substantially pure drinking water can be obtained. Applicant's cooling system does not require pure water. Any water will do if it

is at a proper temperature. However, the water table for drinking water is supplied by the water above and when that water is gone the drinking water table drops. Consequently, applicant's system has this great merit: it withdraws the water and then returns it to the very ground from which it has been taken for reheating or recooling in intimate contact with the ground.

Applicant's system has this advantage over 10 existing closed systems. The heat exchange surface of the closed system is limited to the surface area of the pipe that is in the ground. In applicant's system, the heat exchange takes place by the water filtering through the ground from the point 60 to the point 42. In other words, the water which has lost its heat and which is returned to the ground through the pipe 58 is much more likely to reach a desired higher temperature for return into the system by the pipe 40 after it has worked its way through the ground than is probable where the pipes 58 and 40 are connected to each other into a closed pipe system.

Applicant's system has this advantage: the weight of the water being pumped upwardly 25 through the pipe 40 is balanced by the weight of the water descending the pipe 58 with the result that the pump performs merely a circulating function, and may be of appropriate reduced capacity with correspondingly less power 30 consumption. To convert applicant's system into a semi-closed system, the open top stock tank is replaced by a closed tank, which becomes part of a system full of water commencing with the pipe 40 and terminating with the pipe 58.

35 Returning to Fig. 4, the arrangement of the outlet 52 and the drain 56 makes it possible to withdraw water from the bottom of the tank where the water is coolest. An overflow at 62 is slightly above the desired water level 54.

40 Disposed in the stock tank 50 are a plurality of coils 64. A liquid refrigerant distributor 66 is positioned beneath the coils and this is tapped by lines 68 to the respective coils. The distributor 66 is supplied with refrigerant from two capillaries 70 and 72 which are joined at 14 and supplied from a common capillary 76. The discharge ends of the coils 64 are connected to an accumulator 80, which is a pipe 2 and $\frac{1}{8}$ inches in diameter. Three refrigerant gas suction lines 82, 84 and 86 45 are connected to the top of the accumulator 80 and open into pipes of graduated sizes such as 88 and into a single, main suction line 90.

The apparatus thus far described is housed in an unheated room 92 in applicant's basement, see 50 Fig. 3. The balance of the apparatus is positioned centrally of applicant's basement. The apparatus is clean and can be positioned at the point where the return cool air and hot air from the house can be most efficiently handled.

55 Continuing to refer to the drawings, the suction line 90, is carried into the main basement room near the ceiling and is connected through a reversing valve 94 to a compressor 96 of four-ton capacity. The compressed refrigerant gas 60 leaves the compressor 96 by the duct 98, and after passing through the reversing valve 94 is carried to two lines 100 and 102 which open into the top of an accumulator 104. The accumulator is mounted above a pair of equal capacity finned 65 coils 106 and 108, and pipes 110 and 112 open into the upper inlet opening of the finned coils 106 and 108. The outlets of the finned coils 106 and 108 are connected to a common pipe 114 whose sole outlet is a capillary 116, which 70 tends up to the ceiling and over and joins the 75

capillary 76. The compressor is driven by a five horsepower motor 118. The finned coils 106 and 108 and accumulator 104 are supported on transverse brackets 120 and 122 in a housing 124. This housing is generally separated into two chambers, a warm air chamber 126, and a cold air chamber 128, by a partition 130. The cold air intakes such as 132 open into the top of the cold air chamber 128. A motor driven fan assembly 132a draws the cool air from the chamber 128 and forces it through the fin coils 106 and 108 into the warm air chamber and thence out room ducts such as 134.

The system as shown operates automatically after it has been set as either a heating unit or a cooling unit. Referring to Fig. 4, a power line 136 is connected to a relay 138. The output of the relay is connected by conductors arranged in parallel to the pump motor 46, the compressor motor 118, and the fan assembly motor 133. The relay 138 is actuated from a room thermostat 140. This thermostat is of that type which will close a circuit to a relay either on a falling temperature or on a rising temperature, depending upon how a manually actuated switch in the thermostat is positioned. The electrical wiring shown is conventional and need not be described in detail. At the present time, if applicant wishes to convert the system from a heating system to a cooling system, he manually throws the reversing valve 94. It is evident that the applicant could arrange an electrically operated throw switch connected to the reversing valve 94 and actuate it through a manual switch in the room thermostat 140.

The operation of the apparatus is sufficiently obvious so that it need not be described. It will, of course, be appreciated that the amount of water passed through the tank 58 per hour will vary with the load. It will also vary with the temperature of the water and this temperature does vary substantially from September, when the system is first turned over to heating, to the coldest months. During the month of February, the temperature of the water from the tank from the ground was 56 degrees and the temperature of the water as it left the tank to return to the ground was about 46 degrees. As mentioned above, there will be some fluctuation but it is not sufficiently great to noticeably affect the operation of the apparatus. As for the temperature in the heating coils, on the high side of the compressor, that is, on the side leading to the accumulator 104 and coils 106 and 108, the temperature is about 133 degrees Fahrenheit and the pressure about 190 pounds. On the low side, that is, in the suction line 90, the pressure is about 28 pounds and the temperature is about 30 degrees Fahrenheit. With the temperature of the compressed gas at 133 degrees Fahrenheit, a flow of very warm air can be maintained into the ducts such as 134.

Most important, the first feature resides in the substantially equal volumetric capacity of the two heat exchange units—the first heat exchanger consisting of the accumulator 104 and coils 106 and 108, and the second heat exchange unit consisting of the coil 64 and the accumulator 80. It is the balanced, equal capacity heat exchanger system which makes it possible to dispense with check valves and expansion valves, and this enormously simplifies the reversing of the system from a heating to a cooling unit. It should be borne in mind that applicant is not concerned with slugs of gas mixed with liquid refrigerant.

Applicant has positioned along the capillary tube 76 standard windows so that he can study the condition of the liquid refrigerant from the pipe 114 all the way through the capillary into the coil 64. If the refrigerant going through capillary were free of gas, it would be transparent. If it is not transparent but milky in appearance which indicates the presence of comparatively large quantities of gas vapor. It is, therefore, immaterial in applicant's system whether gas passes along the capillary. However, when a system is operating well, the liquid level will be above the bottom course of pipe in the coils 106 and 108, and the coils 64 will be almost full to the liquid level 54 inside the accumulator 80. With the system in reverse, the liquid level will be above the distributor pipe 66 and the liquid level in the heat exchanger 105 will be up in the accumulator 104. In other words, in this balanced system, the refrigerant charge is such that in whatever direction the refrigerant is flowing, the refrigerant level will be above the capillary inlet on the heat exchanger that is performing the cooling function and will be up in the accumulator in the heat exchanger unit that is performing the heating function. For practical purposes, the capillary is never blown out by gas. It will be appreciated that this becomes of great importance when the system is operated within 24 hours as both a heating and a cooling unit. Many climates where the play between night and day temperatures is very great, fifty or sixty degrees, require a little heating at night and some cooling in the daytime. The situation occurs in many localities in the spring and fall of the year. The advantage of applicant's balanced system is that it can be converted from a heating to a cooling system without any adjustment being made in the refrigerant line itself other than the act of throwing the reversing valve. Applicant's is an open duct system.

The accumulator acts as a muffler. As heretofore mentioned, the pound of the pump is very loud where the shock of the compressed gas is contained in a pipe system of constant diameter 43 prior to liquifying a refrigerant. Applicant's accumulator performs a dual function. When the accumulator is acting in the heat exchanger which is performing the heating function, the accumulator functions as a muffler. On the other hand, when the accumulator is in the heat exchanger which is performing the cooling function, the accumulator with its large surface area for a liquid level assists in rapid boiling of the liquid.

55 The balanced system has value irrespective of the presence of a reversing valve. The use of heat exchangers having substantially equal volumetric capacity eliminates the use of valves in the refrigerant line. Referring to Figs. 3, 4 and 5, if the reversing valve 94 is omitted, applicant's system maintains the correct liquid levels in the two heat exchangers. It should be noted that cold air, referring to Fig. 4, is brought in beneath the coils 106 and 108. The lower end of these coils is comparatively cool because of the presence of liquid refrigerant, and, therefore, has little heat transfer effect upon the air. This is to be contrasted with the ordinary way of applying air to a condenser in a refrigerating system where no care is taken as to the direction of the flow of the air.

Having thus described my invention, what I claim is:

1. A reversible heat exchange system comprising a pair of heat exchangers having approximately equal volumetric capacity, a tube having

a restricted passageway therein connecting the lower portions of said heat exchangers to each other, an accumulator connected to the top of each heat exchanger, a duct connecting each accumulator to a reversing valve assembly, a compressor, and ducts connecting the valve assembly to the high and low side of the compressor, said reversing valve being so arranged that the high side of the compressor can be connected to either accumulator and while so connected, the low side of the compressor will be connected to the other heat exchanger.

2. A reversible heating and cooling system comprising a housing having an inlet and an outlet therein for passing fluid to be heated or cooled through the housing, a heat exchanger consisting of an accumulator tank connected to a coil positioned in said housing, a second heat exchanger positioned outside the housing and having a volumetric capacity substantially equal to that of the first heat exchanger, a tube having a restricted passageway therein connecting the lower portions of said heat exchangers to each other, a compressor, a duct connecting the accumulator tank to the high side of the compressor, a duct connecting the other heat exchanger to the low side of the compressor, and a reversing valve positioned in both of said ducts for connecting the accumulator tank to the low side of the compressor and the second heat exchanger to the high side of the compressor.

3. A reversible heating and cooling system comprising a housing having an inlet and an outlet therein for passing fluid to be heated or cooled through the housing, an accumulator tank mounted in said housing, a coil for refrigerant positioned beneath the accumulator, a plurality of ducts connecting the accumulator tank to the coil, a compressor having a high side and a low side, a duct connecting the high side of the compressor to the accumulator tank, a heat exchanger positioned outside the housing and having a volumetric capacity substantially equal to the combined capacity of the accumulator tank and the coil, a tube having a restricted passageway therein connecting the lower portions of said coil and said heat exchanger, a duct connecting the heat exchanger to the low side of the compressor, and a reversing valve positioned in both of said ducts for connecting the accumulator tank to the low side of the compressor and the heat exchanger to the high side of the compressor.

4. A reversible heating and cooling system comprising a housing having an inlet and an outlet therein for passing fluid to be heated or cooled through the housing, a pair of heat exchangers each consisting of an accumulator tank connected to a coil, one positioned in the housing and the other outside the housing, said heat exchangers having approximately equal volumetric capacity, a tube having a restricted passageway therein connecting the lower portions of said heat exchangers to each other, a compressor, ducts connecting the accumulator tanks to the high and low sides respectively of the compressor, and a two-position valve located in said ducts for reversing their connections to the high and low sides of the compressor respectively.

5. A heat exchange system comprising two heat exchangers having substantially equal volumetric capacity, each heat exchanger consisting of an accumulator tank connected to coils positioned therebelow, a compressor, ducts connect-

ing the accumulator tanks to the high and low sides respectively of the compressor, and a tube having a restricted passageway therein connecting the lower ends of the coils of one exchanger to the lower ends of the coils of the other exchanger.

6. A reversible heat exchange system comprising a pair of heat exchangers having approximately equal volumetric capacity, a capillary tube connecting the lower portions of said heat exchangers to each other, an inlet near the top of each heat exchanger, a duct connecting each inlet to a reversing valve assembly, a compressor, ducts connecting the valve assembly to the high and low side of the compressor, said reversing valve being so arranged that the high side of the compressor can be connected to either heat exchanger and while so connected, the low side of the compressor will be connected to the other heat exchanger, and a liquid refrigerant having a volume approximating the volume of one heat exchanger in the system.

7. A reversible heat exchange system comprising a pair of heat exchangers having approximately equal volumetric capacity, a capillary tube connecting said heat exchangers to each other, a compressor having a high side and a low side, ducts connecting the heat exchangers to the high and low sides respectively of the compressor, one of said exchangers being positioned within a tank, an inlet and an outlet for said tank, a pipe connected to the inlet and extending into the ground, a pipe connected to the outlet of the tank and extending into the ground, and a pump for circulating liquid from the first pipe through the tank and out the second pipe.

8. A reversible heat exchange system comprising a pair of heat exchangers having approximately equal volumetric capacity, a capillary tube connecting said heat exchangers to each other, a compressor having a high side and a low side, ducts connecting the heat exchangers to the high and low sides respectively of the compressor, one of said exchangers being positioned within a tank, an inlet and an outlet for said tank, a pipe connected to the inlet and extending into the ground, a pipe connected to the outlet of the tank and extending into the ground, and a pump for circulating liquid from the first pipe through the tank and out the second pipe at approximately the same level as the intake end of the first pipe.

9. A reversible heat exchanger system comprising a pair of heat exchangers having substantially equal volumetric capacity, each heat exchanger consisting of an accumulator tank connected to coils positioned therebelow, a compressor, ducts connecting the accumulator tanks to the high and low sides respectively of the compressor, a reversing valve positioned in both ducts for reversing the connections of the two accumulators to the compressor, and a liquid refrigerant having a volume approximating the volume of one exchanger in the system.

10. A reversible heat exchanger system comprising a compressor, a reversing valve, ducts connecting the reversing valve to the compressor, a heat exchanger comprising an accumulator and a connected, suspended coil, a duct connecting the accumulator to the reversing valve, a second heat exchanger comprising an accumulator of lesser volume than the accumulator of the first exchanger and connected to a depending coil having sufficiently more capacity than the capacity of the coil of the first exchanger so

that the volumetric capacities of the two exchangers are approximately equal, and a tube connecting the coils for one heat exchanger to the coils of the other heat exchanger, there being a restricted passageway in said tube so that it may act as a refrigerant flow control.
